UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

METHOD OF MAKING SHOES.

1,419,201.

Specification of Letters Patent. Patented June 13, 1922.

Original application filed May 31, 1916, Serial No. 100,950. Divided and this application filed November 12, 1920. Serial No. 423,630.

To all whom it may concern:

Be it known that I, ARTHUR BATES, a subject of the King of England, residing at Leicester, Leicestershire, England, have invented certain Improvements in Methods of Making Shoes, of which the following description, in connection with the accompanying drawings, is a specification, like reference characters on the drawings indicating like parts in the several figures.

This invention relates to methods of making shoes, the present application being a division of my earlier application, Serial No. 100,950, filed on May 31, 1916. An object of the invention is to secure better results than heretofore in the shaping of upper materials, herein generally termed the "upper", over a last or other shoe form. While the invention is herein particularly illustrated in its application to veldtschoen or stitch-down work, it will be evident that in many of its aspects it is not limited to such work but is generally applicable to the manufacture of shoes of various types.

In one important aspect, the invention has particularly in view the shaping of an upper smoothly and free from wrinkles round the end of a shoe form by uniform inwardly directed pressure such as may be applied, for example, by a flexible loop member, herein conveniently termed a "wiper", or other member adapted to conform itself to the contour of the shoe, with the margin of the upper so controlled as to increase the tightening effect of the wiper and to maintain the upper continuously in an unwrinkled condition throughout the upper shaping operation. In accordance with the manner herein illustrated of practicing the method, the margin of the upper is clamped on a continuous line round the end of the form under such control as to give up stock at points where the tension produced by the indrawing pull of the wiper tends to become excessive, thus assisting in equalizing the tension and in maintaining the pressure of the wiper uniform on the different portions of the upper which it engages. With the margin of the upper thus clamped in a smooth and unwrinkled condition and held yieldingly against the pull of the self-conforming wiper in such manner as substantially to equalize the tension and pressure all round the end of the form, the upper is

drawn tightly inward to the contour of the 55 form with no opportunity afforded for the wrinkling of the upper as it is worked into its final shape. In the illustrated practice of the method the margin of the upper is clamped in outspread condition round the 60 end of the form, which assists in holding it free from wrinkles; and in the making of stitch-down shoes it is contemplated that the margin will thus be shaped or molded to produce an out-turned sole-attaching flange 65 characteristic of this type of shoe.

In a further aspect, the invention has in view the stretching and shaping of the upper over the top of the form with the margin under such control as to give up 70 stock round the end of the form at points of excessive tension and thereby substantially to equalize the tension over the high and low parts of the contour of the form. The illustrated manner of practicing this 75 part of the invention consists in pulling and stretching the upper heightwise of the form while clamping the margin yieldingly on a substantially continuous line round the end of the form, and independently gripping 80 portions of the margin farther rearwardly along the sides of the form and drawing the upper forwardly at the sides as well as at the end of the form while pulling it heightwise of the form. In this manner the 85 strains on the different portions of the upper round the end of the form are substantially equalized irrespective of the contour of the form and the entire end portion of the upper is subjected also to a foredrawing tension 90 without relative displacement of parts at the end and the sides such as might tend to distort the line of the tip seam where the shoe is provided with a tip seam. When this part of the invention is combined in 95 practice with the shaping of the upper round the end of the form in the manner hereinbefore set forth, the forepart of the upper is completely shaped to the contour of the form without substantial differences in the 100 strains applied at different parts, such as might lead to loss of shape in the wear of the shoe, and without wrinkles in the parts of the shoe which have been found heretofore particularly difficult to shape in a 105 smooth and satisfactory manner.

In a further aspect of the invention it is contemplated that after the upper has been

shaped, as by drawing it to the contour of the form under such control as hereinbefore set forth, it will be held in shape by the application of retaining means, for example 5 by applying a flexible binder round the end of the shoe and anchoring it to the shoe. In stitch-down work the binder may conveniently lie in the crease at the inner boundary of the out-turned flange of the 10 upper and will preferably remain in place until after the flange has been secured to a sole or insole. The binder may be anchored in any suitable way, for example by fastening it to the upper at the opposite sides of 15 the shoe. The use of a binder round the toe of a stitch-down shoe to assist in holding the upper in shape prior to the sewing operation is new as far as I am advised, and I desire to protect it irrespective of the 20 particular manner of shaping the upper.

While the invention is applicable to the shaping of uppers over lasts which remain in place while subsequent manufacturing operations are performed, the invention has 25 further in view the use of some or all of the method steps hereinabove set forth in a strictly molding operation in which the upper is withdrawn from the mold and is subsequently applied to a last for later operations. In such procedure the upper will be 30 shaped, for example, over a metal form or mold corresponding generally in size and shape to a portion at least of the last to be subsequently used. In such a molding operation the binder may be anchored to the 35 upper itself and will assist in retaining the upper in molded shape while it is removed from the form and mounted on its last. While the invention thus has in contemplation 40 both what is commonly known as lasting and what is more generally understood as molding, the term "form" is herein used in a generic sense as applicable to a last or equivalent member over which the upper is 45 shaped, except where the context requires a more limited interpretation of the term as distinct from what is commonly understood as the last.

The novel method of this invention, in the 50 above mentioned and other aspects, will now be more particularly set forth by reference to the accompanying drawings which illustrate the various steps and show one form of apparatus by the aid of which the method 55 may be practiced, such apparatus being more fully shown and described in my prior application of which this is a division.

In the drawings:

Fig. 1 is a view illustrating the treatment 60 of a shoe, in accordance with one manner of practicing the method, by the aid of the machine shown and described in said prior application, the machine being shown in side elevation with parts in section;

Fig. 2 is a transverse sectional view illus-

trating more fully the means for pulling the upper at the sides;

Fig. 3 illustrates more fully the operations of clamping and pulling the upper and of drawing it inwardly by the flexible wiper;

Fig. 4 shows a stitch-down shoe upper held in shape round the toe by means of a toe binder, the upper having been removed from a form over which it was molded, and

Fig. 5 shows the upper with an insole applied and stitched to the out-turned flange of the upper.

For pulling the upper the machine has a support 1 for a shoe form or last, mounted to swing upwardly about a fixed pivot 2 relatively to means which grips and clamps the margin of the upper, the support 1 being engaged and operated by a plunger 4 pivoted on the left hand end of a lever 5 which is mounted on a pivot 6 and has its right hand end forked and connected by links 8 to a vertically movable cross-head 9. Slidable lengthwise in the cross-head 9 is a rod 10 provided with an abutment 12 for engaging the cross-head to move it downwardly, the rod 10 being adjustably connected with a lower cross-head 15 which is in turn connected by links 16 to a link 18 operated by an eccentric 20 on a power shaft 21. This construction affords provision for initial downward movement of the rod 10 relatively to the cross-head 9 prior to the engagement of the abutment 12 with said cross-head in order to permit the side grippers and the upper clamping means, which are also operated by the rod 10 as will be described, to seize and clamp the upper before the support 1 is moved to raise the shoe form.

For clamping the margin of the upper in outspread condition round the toe two flat 105 plates 30 and 31 having recesses of substantially U-shape are provided, the plate 30 being rigidly mounted and the plate 31 being supported loosely on a plunger 35 between a shoulder of which and a collar 36 the plate 110 is confined. The plate 31 is overlaid by a cap 38 having a convex top face fitting a concave lower face of the collar 36 so that the plate may tip to adjust itself to the work. A spring 39 is confined between the 115 shoulder on the plunger 35 and a shoulder on the cap 38 to maintain the curved faces in contact, and a pin 37 serves to guide the plate 31 and to limit its tipping movement.

The upper plate 31 is moved downwardly 120 to clamp the margin of the upper by a lever 40 connected to the plunger 35 and fulcrumed at its right hand end to a post 42. The rod 10 extends loosely through the lever 40 and above the lever carries a spring 45 125 through which the upper clamping pressure is applied. A second and weaker spring 46 is confined between the lever and the frame, and the rod has collars 47 and 48 which in the movements of the rod up and down act 130

respectively to relieve the lever of the pressure of the springs 45 and 46. It will be understood that the upper plate 31 is moved through these connections yieldingly to 5 clamping position while the rod 10 is moving relatively to the cross-head 9 and before the abutment 12 becomes effective to raise the support 1.

For pulling the upper at opposite sides at 10 the rear of the toe, the machine has side grippers, Fig. 2, arranged to engage the upper at opposite sides of the form to pull the upper transversely and forwardly at the rear of the toe clamping plates while the latter are 15 acting to pull the upper heightwise and lengthwise of the form. These grippers each comprise an inner jaw formed on a tubular bar 50 which is vertically movable in a guide 52 and is normally upheld by a spring 20 54, and an outer jaw 55 pivoted to the inner jaw and connected by a link to an operating rod 56. The rod 56 is movable in the bar 50 and in the guide 52 through a link connection with a cross bar 60 which is pivotally 25 mounted on a horizontal bar 62 to constitute an equalizer between the side grippers and to be manually operated to shift the upper transversely of the form. The bar 62 is carried by a vertically movable rod 65 which is 30 moved downward yieldingly through a spring 66 by means of a lever 70 which is fulcrumed on the frame and connected to the link 18.

The side gripper guides 52 are pivotally 35 supported on a slide 72 and are adjustably connected together by a right and left threaded rod 73 to permit them to be spaced variably for different widths of shoes. The slide 72 is mounted on a stationary bar 74 40 extending lengthwise of the shoe and is moved along said bar to impart foredrawing movement to the side grippers through a rod 75 which is also adjustable to position the grippers for different lengths of shoes. Operative 45 movement is imparted to the rod 75 by a lever 80 which is fulcrumed on a short link 78 on the frame and is connected by a link 79 to a lever 82 fulcrumed on the bar 74, the lower end of this lever being connected 50 by a link 83 to the right hand end of the vertically movable bar 62. It will thus be evident that when the bar 62 is moved downwardly for operating the side grippers to pull the upper the lever 82 is operated by 55 the link 83 to swing the lever 80 in a direction for advancing the side grippers along the bar 74 toward the toe end of the shoe.

For drawing the upper round the toe into conformity to the lateral periphery of the 60 form a wire loop wiper, or like flexible wiper, 85 extends round the end of the shoe and is attached at its ends to the upper forked end of the lever 80. The flexible wiper is thus operated to perform its function co-ordinately with the relative move-

ments of the form and the upper clamping means and the grippers to stretch the upper and draw it over the form.

From the foregoing description it will be evident that when the last or form, with or 70 without an insole on its tread face, is mounted on the support 1 with the margin of the upper between the side gripper jaws and outspread round the toe between the clamping plates, the first operation is to close the 75 grippers and to clamp the margin of the upper round the toe, whereupon the support 1 is swung upwardly and backwardly to cause the grippers and the clamping means to pull the upper heightwise and forwardly of the 80 form, downward pulling movement and foredrawing movement being imparted to the side grippers at the same time through the connections described. It will be understood that the flexible wiper 85 is sufficiently loose 85 at the start to prevent it from having any substantial drawing action on the upper until after the latter has been pulled to some extent. During the upper pulling operation and during the rearward drawing action of 90 the wiper 85 the yieldable clamping means permits the margin of the upper to slip at any point where an excess of tension is applied and this serves to equalize the strains over the high and low parts of the form in 95 the pulling of the upper heightwise and forwardly of the form, and also to equalize the pressure of the flexible wiper on the different portions of the upper in the operation of drawing it inwardly to the contour of the 100 form. As the flexible loop wiper 85 is pulled rearwardly it adapts itself at all points to the contour of the work and thus brings uniform pressure to bear at the different points while drawing the upper closely and 105 uniformly to the contour of the form. In stitch-down work the length and the extent of movement of the flexible wiper will be so determined as to shape the upper as required with a crease extending along the 110 edge of the shoe bottom at the inner boundary of the out-turned flange, and in this class of work also the upper clamping means will serve to shape the margin of the upper as required to produce the out-turned flange. 115 It will be further evident that by clamping the margin of the upper continuously round the toe from one side to the other in an outspread condition and by using a flexible wiper to draw the upper into lasted position 120 while the margin is thus controlled by the clamping means and permitted to slip at any point where an excess of tension is produced, insurance is afforded against the formation of objectionable wrinkles along the edge of 125 the shoe bottom and the upper is shaped smoothly and uniformly to the contour of the form at all points round the toe.

After the upper has been shaped to the form in the manner above described, it is 130

contemplated that the machine will come to a stop. A suitable retaining means, such as a toe binder wire, may then be applied in the crease formed by the flexible wiper and anchored at its ends in any suitable manner. When the machine is again started the parts are returned to their starting position and the shoe is released with the upper held in shape round the toe by the binder.

10. If desired, and as herein illustrated, the upper is prepared for treatment as above described by first molding the heel portion of the upper materials as a special molding operation such as described in prior United States Letters Patent No. 1,156,897, and when this step of molding the heel seat is included the shoe is ready for the shoe bottoming operations, with the aid sometimes of more or less shank lasting. In the making of stitch-down shoes the binder applied round the toe will preferably remain in place to assist in holding the upper in the required shape until after the out-turned flange of the upper has been sewed to a sole or insole.

It is further contemplated, in one use of the method of this invention, that instead of shaping the upper over a form such as a last, which is to remain in the shoe until the manufacturing operations have been completed, the last may be replaced by a mold which may or may not fill the entire shoe, and the operations herein described will then have more particularly the character of what is commonly understood as molding. In such use of the mold the toe binder may be fastened to the upper itself, as by inserting its ends through small holes formed in the out-turned margin of the upper and bending the ends under the marginal flange to retain the binder in place. After the molding operation the upper will be removed from the form and the binder will assist in holding it in shape, as indicated in Fig. 4. Subsequently the upper will be mounted on a last and sewed, for example, to an insole, as illustrated in Fig. 5. The wire binder may then be conveniently removed from the shoe by pulling its ends out of the holes in the flange.

Having explained the nature of the invention and set forth fully how it may be practiced, what I claim as new and desire to secure by Letters Patent of the United States is:—

1. That improvement in methods of making shoes which consists in mounting an upper on a shoe form, holding the upper free from wrinkles round the end of the form, and while holding it free from wrinkles drawing it inwardly round the end of the form by the aid of a flexible wiper conformable at all points to the contour of the shoe.

65 2. That improvement in methods of mak-

ing shoes which consists in mounting an upper on a shoe form, clamping the margin of the upper outspread on a substantially continuous line round the end of the form and holding the upper free from wrinkles, and while the upper is thus clamped and controlled drawing it inwardly round the end of the form by the aid of a flexible loop wiper conformable at all points to the contour of the shoe.

3. That improvement in methods of making shoes which consists in mounting an upper on a shoe form, clamping or gripping the margin of the upper round the end of the form, and then drawing the upper inwardly round the end of the form by aid of a flexible wiper while giving up stock from the clamped margin at any point or points where an excess of tension is produced by the indrawing pull of the wiper.

4. That improvement in methods of making shoes which consists in mounting an upper on a shoe form, clamping or gripping the margin of the upper round the end of the form, and then, while permitting the clamped margin of the upper to slip at any point or points where an excess of pulling tension is applied, pulling and stretching the upper substantially heightwise of the form and drawing it inwardly round the end of the form by the aid of a flexible wiper conformable at all points to the contour of the shoe.

5. That improvement in methods of making shoes which consists in mounting an upper on a shoe form, clamping the margin of the upper on a substantially continuous line round the end of the form and pulling it over the top and outwardly from the end of the form while giving up stock from the clamped margin at points where an excess of tension is applied, and while the upper is thus clamped pulling it inwardly to the contour of the form by the aid of a flexible wiper conformable at all points to the contour of the shoe.

6. That improvement in methods of making shoes which consists in mounting an upper on a shoe form, clamping the margin of the upper outspread on a substantially continuous line round the end of the form and holding the upper free from wrinkles, and with the upper thus clamped and controlled pulling it heightwise of the form and by the aid of a flexible loop wiper also drawing it inwardly to the contour of the form while giving up stock from the clamped margin at points where an excess of tension is applied.

7. That improvement in methods of making shoes which consists in mounting an upper on a shoe form, clamping the margin of the upper round the end of the form and pulling it heightwise of the form while giving up stock from the clamped margin

at points where an excess of tension is applied, and while increasing the pulling strain on the upper heightwise of the form drawing it inwardly round the end of the 5 form by the aid of a flexible loop wiper conformable at all points to the contour of the shoe.

8. That improvement in methods of making shoes which consists in mounting an 10 upper on a shoe form, clamping the margin of the upper free from wrinkles on a substantially continuous line round the end of the form and pulling it heightwise of the form, and drawing the upper inwardly 15 round the end of the form by the aid of a flexible loop wiper while giving up stock from the clamped margin at points where an excess of tension is applied in drawing the upper inwardly.

20 9. That improvement in methods of making shoes which consists in mounting an upper on a shoe form, clamping the margin of the upper outspread on a substantially continuous line round the toe end of the 25 form and independently gripping portions of the margin farther rearwardly at the sides of the forepart, pulling the upper heightwise of the form while it is thus clamped and gripped at the toe and the 30 sides, and during the pulling of the upper giving up stock from the clamped margin round the toe at any point or points where excessive tension is applied to shape the 35 upper over the high and low portions of the contour of the form under substantially uniform tension.

10. That improvement in methods of making shoes which consists in mounting an upper on a shoe form, clamping the margin 40 of the upper on a substantially continuous line round the toe end of the form and independently gripping portions of the margin farther rearwardly at the sides of the forepart and then pulling the upper 45 heightwise of the form and also forwardly round the toe and at the sides, and during the pulling of the upper giving up stock from the clamped margin round the toe at any point or points where an excess 50 of pulling tension is applied to equalize the tension over different portions of the contour of the form.

11. That improvement in methods of making shoes which consists in mounting 55 an upper on a shoe form, clamping the margin of the upper round the toe end of the form and also gripping the margin at opposite sides of the ball of the shoe and pulling the upper both heightwise of the form 60 and forwardly at the toe and the sides, and while the upper is held under tension at the toe and the sides working it inwardly to the contour of the form on a continuous line round the toe.

65 12. That improvement in methods of

making shoes which consists in mounting an upper on a form, clamping the margin of the upper on a substantially continuous line round the end of the form and holding the upper free from wrinkles, and while the 70 upper is thus clamped and controlled drawing it inwardly round the end of the form by the aid of a flexible loop wiper adapted to accommodate itself automatically at all points to the contour of the shoe, and 75 then applying a binder round the end of the shoe and removing the flexible wiper for use on another shoe.

13. That improvement in methods of making stitch-down shoes which consists in 80 mounting an upper on a form, clamping the margin of the upper outturned on a substantially continuous line round the toe end of the form, and then drawing the upper inwardly to the contour of the form by the aid 85 of a flexible wiper while holding the margin clamped and shaping it to produce an outturned flange adapted to be secured to the sole or insole of the shoe.

14. That improvement in methods of making stitch-down shoes which consists in 90 mounting an upper on a form, clamping the margin of the upper outturned on a substantially continuous line round the toe end of the form, and then pulling the upper height- 95 wise of the form and by the aid of a flexible loop wiper drawing it inwardly to the contour of the form while giving up stock from the clamped margin at points of excessive tension and shaping the margin to produce an outturned flange adapted to be secured to the sole or insole of the shoe.

15. That improvement in methods of making stitch-down shoes which consists in molding the heel portion of an upper to produce 105 an inturned heel seat flange, mounting the upper on a form, clamping the margin of the forepart of the upper outspread in a plane substantially parallel to the plane which the outturned flange of the upper is to 110 occupy in the completed shoe, and while the upper is thus clamped pulling it heightwise and lengthwise of the form and drawing or wiping it inwardly to the edge of the form round the toe and confining it in that relation to the form.

16. That improvement in methods of making stitch-down shoes which consists in pulling and stretching an upper over the top face of a form and shaping the margin of 120 the upper to produce an outturned sole attaching flange, and drawing the upper to the edge of the form round the toe and binding it against outward movement away from the edge of the form.

17. That improvement in methods of making stitch-down shoes which consists in shaping an upper over a form and molding the margin of the upper to produce an outturned sole attaching flange, applying a binder 130

round the end of the form to hold the upper in shape, and securing the outturned flange of the upper to a sole while the binder remains in position to hold the upper.

5 18. That improvement in methods of making stitch-down shoes which consists in pulling an upper over a form at the forepart and shaping the margin of the upper to produce an outturned sole attaching flange, applying a binder round the toe to hold the upper and fastening the binder at the opposite sides of the forepart, securing the outturned flange of the upper to a sole while the binder remains in position to hold the upper, and subsequently removing the binder.

10 19. That improvement in methods of making shoes which consists in molding an upper over a form to shape it to the contour of the toe end of the form, applying a binder

round the toe and fastening it to the upper to hold the upper in molded shape, removing the upper from the form and mounting it on a last while the binder remains in position to hold the upper in shape, and subsequently securing the upper to a sole or insole. 25

20. That improvement in methods of making stitch-down shoes which consists in molding an upper over a form to shape it to the contour of the form and to produce an outturned sole attaching flange, applying a binder round the end of the upper and fastening it to the upper alone, removing the upper from the form and mounting it on a last, and then securing the outturned flange of the upper to a sole or insole. 30 35

In testimony whereof I have signed my name to this specification.

ARTHUR BATES.
